UNITED STATES PATENT OFFICE.

FREDERICK D. HILL, OF NEW YORK, N. Y., ASSIGNOR OF TWO-THIRDS TO
GEORGE W. NELSON AND JACOB S. FREER, OF SAME PLACE.

BURGLAR-ALARM.

SPECIFICATION forming part of Letters Patent No. 284,012, dated August 28, 1883.

Application filed May 22, 1883. (Model.)

To all whom it may concern:

Be it known that I, FREDERICK D. HILL, of the city, county, and State of New York, have invented a new and useful Improvement in 5 Burglar-Alarms, of which the following is a full, clear, and exact description.

Reference is to be had to the accompanying drawings, forming a part of this specification, in which similar letters of reference indicate 10 corresponding parts in all the figures.

Figure 1 is a side elevation, partly in section, of my improvement. Fig. 2 is a front elevation of the same, partly in section and part being broken away. Fig. 3 is a sectional 15 plan view of the same, taken through the line xx , Fig. 1.

The object of this invention is to facilitate the attachment of alarms to door-knobs, and promote certainty in the operation of such 20 alarms.

The invention consists in a burglar-alarm constructed with a spring-clamp connected with a bar jointed to a suspended frame carrying a clock-work and gong, and a sliding 25 rod provided with a spring, and having fingers to engage with the escapement-anchor, and a catch attached to the suspending-bar, whereby the alarm can be readily suspended from a door-knob, and will be sprung by the 30 movement of the said knob, as will be herein-after fully described.

A represents a small frame, to which is attached a clock-work, B, and one or more gongs, C. The upper end of the frame A is 35 loosely jointed to the lower end of the bar D, to the upper end of which is attached, or upon it is formed, a forked arm, E. The forked arm E is so shaped as to fit upon the upper side of any ordinary door-knob, R.

To the bar D is hinged, or with it is otherwise connected, an arm, F, which is made elastic, or is held up by a spring, G, connected with it and with the said bar D. The arm F is so formed as to fit against the lower 45 side of an ordinary door-knob, so that the bar D will be securely clamped to the said door-knob, and when the said knob is turned the said bar D will be carried with it.

With the escapement-anchor H of the clock-work B is rigidly connected the bell-hammer

I, which is so formed as to be thrown against the gong or gongs C by the vibration of the said escapement-anchor H.

J is a rod which passes through the upper gong C, and through a guide, K, attached to 55 the frame B. The lower end of the rod J is bent inward to form a finger, L, or has an inwardly-projecting finger, L, attached to it. The finger L passes in beneath the escapement-anchor H, or beneath the shank of the 60 bell-hammer I, rigidly connected with the said escapement-anchor H, so that the rod J, when raised, will press the said escapement-anchor against the escapement-wheel of the clock-work B, and thus lock the said clock-work. 65

To the upper end of the rod J is attached, or upon it is formed, a finger, M, which projects inward to rest when the said rod J is raised to lock the clock-work upon a catch, 70 N, attached to the bar D.

Upon the rod J is placed a spiral or other shaped spring, O, the lower end of which rests upon a collar or pin, P, attached to the said rod J, and its upper end rests against a guide, Q, attached to the frame A, so that the said 75 spring will be compressed when the said rod J is raised and hung upon the catch N.

If desired, the catch N may be covered by a cap, sliding upon the upper part of the bar D, to prevent the finger M from being accidentally pushed off the catch N when winding up the spring of the clock-work or when applying the alarm to the door-knob. With this construction, when the door-knob is turned the bar D will be turned with it, while the 80 frame A and its attachments will be held vertical by gravity, causing a movement in the joint connecting the bar D and frame A, which movement carries the finger M off the catch N, and allows the rod J to be thrown downward by the elasticity of the spring O, releasing the clock-work and allowing the hammer I to be operated to sound an alarm by the movement of the escapement. 85

If desired, the alarm may be suspended from 90 any suitable support, and connected with a door or window by a cord or wire, so that the alarm will be sprung by any movement of the said door or window.

I am aware that alarms similar to mine 95

have before been attached to door-knobs, in which the turning of the knob throws out of line the joint of a pendulum containing the alarm-bell and clock-work to sound the same, thus 5 freeing the means of restraining the clock and allowing it to sound the alarm, and I do not claim the same, broadly, as my invention.

Having thus described my invention, I claim as new and desire to secure by Letters Patent—
10 1. The combination, with an alarm-gong, clock-work for sounding it, an escapement in the clock, and a jointed connection adapted to suspend the alarm upon a door-knob, the portion above the joint being provided with a
15 fixed catch, of a vertically-sliding rod, a spring forcing said rod downward, a finger at its top to rest on said fixed catch, and a finger at its

lower end adapted to hold the escapement engaged, whereby the turning of the knob will disengage the catch from the upper finger, 20 freeing it to be forced loose from the escapement, and allowing the gong to be sounded, as described.

2. In a burglar alarm, the combination, with the suspending-bar D, carrying the operating 25 parts of the mechanism, of the forked arm E and the spring-arm F, substantially as herein shown and described, whereby the alarm can be readily secured to and suspended from a door-knob, as set forth.

FREDERICK D. HILL.
